PROCESSING TABLE

Walter A. Schwerin, Peoria, and Theodore H. Schonwise, East Peoria, Ill.

Application December 14, 1933, Serial No. 702,282

8 Claims. (Cl. 45—31)

This invention pertains to work tables or benches provided with tiltable tops, and especially for use in food processing, particularly in the meat processing industry.

5 An object of the invention is to furnish a work table, preferably of metal, having a tiltable top and constructed and arranged to withstand very heavy use, and every portion of which may be readily and thoroughly cleaned.

10 Another object is to furnish a work table with a tiltable top portion thoroughly braced throughout and fully supported along its longest edges so as to withstand heavy weights that may be imposed thereon.

15 Still another object is to provide a work table with a tiltable top reversible for easy and thorough renovation, and to include a supporting member along both of its longitudinal edges one of which members is movable whereby to release said top in order that it may be swung freely upon its supports.

Besides these objects the invention includes various structural advantages as will appear herein aided by the appended drawings where- 25 in—

Figure 1 shows a table in perspective constructed according to our invention. Figure 2 is a sectional view taken on line 2—2 of Fig. 4. Figure 3 shows in perspective the under side 30 of the table top showing certain bracing structures. Figure 4 is a front elevation of a table of slightly different proportions from that shown in the earlier figures and produced on a smaller scale than Figure 2. Figure 5 illustrates in perspective a part of the framing of the table and part of the table-top, and Figure 6 is a trans- 35 verse section, in elevation, of a portion of the table parts produced on line 6—6 of Figure 4.

In institutions commonly referred to as "packing houses", where meats are processed, it has been customary to provide wooden tables or benches on which to cut and otherwise treat the meats. Owing to the fact that besides being made of wood and difficult to clean, the table- 40 top upon which the work is done is a fixed member requiring, in an attempt to maintain as nearly as possible a sanitary condition, that the attendant must not only scrape, wire-brush and wash all surfaces with water but must also clean the under surface of the top member by working beneath the latter in order to be sure of some semblance of the cleanliness required by government sanitation inspectors. Quite naturally, it is almost if not entirely impossible to 45 maintain a thoroughly sanitary condition of a table having a fixed top and especially if it be of wood, and in view of this we have devised a table of the type to be described.

In the figures of the drawings a framing is 50 provided of angle iron, for example, there be-

ing end top members 1, 1 supported on legs 2 which may be integral therewith or which may be attached thereto as by welding rather than by such other means as would provide lodgements for bacteria-forming substance. The two end members thus provided are connected by a rear top member 3, again as by welding, and are connected at the front by a member 4 attached at its ends to the front legs 2 some distance below the level of said top members 1, 1, about as shown, there being a central supporting leg 5, by preference, for said member 4. A top member 6 of sheet metal is next provided, which is preferably of a type resistant to corrosion, from one of whose sides at each end thereof, and at the middle of its width, extends an arm 7 provided each with a hole 8 for receiving a stud or bolt 9, Figure 2, to extend through an end member 1, serving to pivotally support the said top and permit tilting thereof as shown in the first two figures. This top 6, which may have greater or less length, depending upon the particular purpose for which it is to be used, is relatively thin, say one-eighth to one-quarter of an inch, in order to obtain comparatively light weight and to hold down the cost, and therefore a strengthening and stiffening structure is provided somewhat as shown in Figure 3. That is to say, between the mentioned arms 7 are spaced arms 10, all of the arms carrying a rod 11 to which are welded the spaced apart arms 12, and finally a truss-rod 13 extends over the ends of the last named arms and is welded at its ends to the rod 11 in about the position shown. This, as may be seen, provides an exceedingly strong and rigid work-supporting structure of comparatively light weight. However, any equivalent arrangement may be used that will serve the purpose.

The top 6 when in its work supporting position lies at one edge upon the rear member 3, the top surface of the latter, if desired, being made to lie below the top surfaces of the end members 1 in order to provide a flush working surface throughout as suggested in Figure 5. At the front of the table, however, the front edge of the top is supported by a structure which may comprise, for example, a lever-arm 14 pivotally mounted on each of the front legs 2 each of which is supported by a stud or bolt 15 mounted in a bearing 16 secured to each said leg. Extending between and mounted in the extremities of the two lever-arms is a rod 17 held in the position shown in Figure 2 by a latch 18 pivoted at 19 on one of the legs and engaged over a part of an adjacent lever-arm, the latter having a convenient handle-portion 19' for operating the structure. Affixed to the rod 17 is a supporting arm or prop 20 which, as shown in

Figure 4, rests upon the member 4 just above the leg 5.

As particularly shown in Figure 4 the structure just described supports the front edge of the top 6 throughout its entire length, as does the member 3 at the rear edge, which is most important, and one of the objects of the invention, since extremely heavy weights are often carried by the said top, it being clear that the truss arrangement 11, 12, 13 together with the supports for the said edges of the top provide a heavy duty type of table.

In Figure 2 the rod 17 is shown in dotted lines in a lowered position and out of the path of travel of the front edge of the top so that the latter may be swung freely to any position, see also Figure 1. When the latch 18 is lifted to release the lever-arm 14 the rod 17 can be moved downwardly to a position where the top 20 6 will pass it at such times as cleaning and renovation of the table is to take place, it being noted that the member 4 in lying well below the top level of the framing is outside the path of travel of the top's edge. Due to the fact that the top 25 6 can be turned completely over, see dotted lines *a* in Figure 2, it may be thoroughly washed on its under surface as required and without the necessity of the attendant getting beneath the table. In this connection it is observed that 30 one of the flat faces of each of the top angle members 1, 3 lies inwardly or toward the inner space enclosed by the table members and therefore can be readily cleaned and consequently cannot retain deleterious matter. Clearly, the 35 fact that the top can be reversed in position so as to be properly cleaned where it is practically impossible to renovate the under side of a fixed top is of prime importance coupled with the fact that the balance of the table, particularly 40 since made of metal, can be cleaned of all bacteria forming matter.

While we have shown a preferred form of our improved table we may make changes therein without departing from the spirit of the invention and the claims thereto.

What we claim is:

1. A table including a framing, a top pivotally mounted at two opposite edges on said framing and arranged to swing to various positions with 50 in the latter, said framing including a permanently fixed supporting portion as a part thereof lying in the path of travel of one of the other edges of said top for receiving and supporting that edge upon it, and said framing having an 55 open side opposite said portion, and a swingable supporting portion pivoted on the framing at opposite sides of said open side to receive the remaining edge of the top and arranged to swing from beneath said remaining edge for the release thereof.

2. A table including a framing, a top pivotally mounted on the framing at two opposite edges, said framing having a supporting member for receiving upon it the full length of one of the other edges of said top, and a member carried by the framing adapted to receive upon it the full length of the remaining edge of the top, said member being pivotally mounted on the framing and being adapted to swing from beneath the 65 top, thus providing a free space to permit said top to freely swing to various positions.

3. A table including a framing, a top pivotally supported between two of its opposite edges thereon, said framing including a member to receive upon it one of the other edges of the top, and being open opposite said member to permit the remaining edge of said top to swing therethrough, a movable member pivotally supported on the framing including a rod having a length substantially equal to the length of the top at the said open side of the framing, said member adapted to be moved into and out of the path of movement of the edge that it supports.

4. The invention according to claim 3 including means to secure the pivotally supported member in the top supporting position.

5. A table including a framing, a top pivotally supported between two of its opposite edges thereon, said framing including a member to receive upon it one of the other edges of the top, the framing being open opposite said member to permit the remaining edge of the top to swing therethrough, and a member including a pair of arms each pivoted to the framing portions that support the pivoted edges of the top, and including a rod extending substantially the full length of the top between its said pivoted edges, said rod adapted to be stationed beneath the edge of the top that swings through the open side of the framing to support the same, said rod having an arm at substantially the middle 100 of its length adapted to rest upon a support in the top supporting position of said rod.

6. A table including a framing, a top pivotally supported at two of its opposite edges on opposite portions thereof, said framing having a supporting member at one of its other sides to receive upon it one of the other edges of the top, the framing having an open side opposite the remaining free edge of said top through which said edge is free to swing to various positions, 110 a supporting structure for supporting the said free remaining edge of the top, the same comprising a pair of arms pivoted on the framing adjacent said open side thereof including a rod extending between said arms adapted to swing 120 beneath and to support upon it the said free edge of the top, and a latch for engaging and securing one of the arms in the top supporting position.

7. The invention according to claim 6 wherein 125 a supporting arm extends from the rod and abuts upon a part of the framing when the rod is in the top-supporting position.

8. A table including spaced end portions, a top pivotally supported at two of its edges thereon 130 adapted to be reversed in position, an arm extending from said top near each of said edges substantially perpendicular to the plane of said top, and each pivoted near its base to one of said end portions, an arm extending 135 from the top between the positions of the first named arms and on the same side from which the latter project, a rod extending through all of the arms, an arm extending from the rod between the positions of the said first named 140 arms, and a truss rod extending across the last named arm and fixed at its ends with respect to the first named rod near the extremities thereof.
